UNITED STATES PATENT OFFICE.

EDWARD INGRAHAM, OF BRISTOL, CONNECTICUT.

DESIGN FOR A BELL-STAND.

SPECIFICATION forming part of Design No. 13,316, dated September 26, 1882.

Application filed August 18, 1882. Term of patent 14 years.

To all whom it may concern:

Be it known that I, EDWARD INGRAHAM, a citizen of the United States, residing at Bristol, in the county of Hartford and State of Connecticut, have invented and produced a new and original Design for a Bell-Stand, of which the following is a specification, reference being had to the accompanying drawings, forming part thereof.

10 Figure 1 is a front elevation of my newly-designed bell-stand with bell attached thereto, and Fig. 2 is a side elevation of the same.

15 A designates the shank, having its upper end rounded in the middle, as at a, and extending laterally therefrom, both to the right and left, there are wings b b in the form of conventional leaves. The lower end of the shank is carved outward and joins the horizontal bar c near the middle of its length. The bar c is 20 joined by the bars d d of the same length and

the shorter bars e f, said bars forming right angles at the several points of connection with each other. At the inner end of the short bar f, and in the center of the figure formed by the bars c, d d, and e, is the central hub, B, 25 having a square contour at its base or back side and a round contour at its front, as shown.

I claim—

The design for a bell-stand herein shown and described, the same consisting of the shank A 30 a b b, the bars c d e f, forming right angles at the several points of connection with each other, and the central hub, B, inside of said bars, and having the round and square contours, respectively, at its front and rear side. 35

EDWARD INGRAHAM.
